CARD PUNCHING MACHINE

Karl J. Braun, Merrick, N. Y., assignor to Control
Instrument Company, Inc., Brooklyn, N. Y., a
corporation of New York

Application December 20, 1944, Serial No. 569,061

50 Claims. (Cl. 164—112)

This invention relates to improvements in statistical card punching machines and has particular reference to machines of the kind wherein the cards are punched column by column.

An object of the invention is to provide an improved punching machine of the portable type which is practical and positive in operation, and wherein a plurality of punches are controlled from a keyboard to perforate a card supported on a carriage having step-by-step movements relative to said punches, which movements are under the control of an escapement that is operated upon each actuation of a key.

Another object is to so control the punching of a card that in the interval between the completion of the punching operation in any column and the restoration of a punch to normal, all of the actuator elements for said punches are similarly disabled to thereby prevent a punching operation of any punch during said interval.

A further object is to mechanically operate the carriage escapement in such manner that upon completion of the concurrent operative strokes of a key and its punch, the latter will start its return stroke and, through such movement, control the escapement so that the carriage will be more readily and quickly advanced independently of the return stroke of said key.

A still further object is to provide the machine with an improved form of skip mechanism by means of which the card carriage is made to move over a field of a card and automatically stop at a predetermined point without the accomplishment of a punching operation. According to this object, the carriage escapement is latched in a release position by the rotative movement of a shaft until said carriage has moved to a predetermined point, whereupon said shaft is moved linearly to release the latching means and thereby permit restoration of the escapement to hold said carriage at said point.

The above and other objects will appear more clearly from the following detailed description when taken in connection with the accompanying drawings which illustrate a preferred embodiment of the inventive idea; but it is to be expressly understood that said drawings are employed merely for the purpose of facilitating the description of the invention as a whole and not to define the limits thereof, reference being had to the appended claims for this purpose.

In the drawings—

Fig. 1 is a fragmentary top plan view of a punching machine constructed in accordance with the invention.

Fig. 2 is a transverse section on the line 2—2 of Fig. 1.

Fig. 3 is a similar section on the line 3—3 of Fig. 1.

Fig. 4 is a longitudinal section on the line 4—4 of Fig. 1.

Fig. 5 is a similar section on the line 5—5 of Fig. 1.

Fig. 6 is a fragmentary sectional view illustrating an intermediate position of an operated punch actuator in its relation to other inactive actuators and to a support therefor.

Fig. 7 is a view similar to Fig. 6 showing the position of the operated actuator after leaving the position of Fig. 6 and during its return or secondary movement to normal position, which movement is utilized to render inoperative the actuator support so that all actuators will be disabled while said return movement is in progress.

Fig. 8 is a fragmentary isometric view showing the release mechanism for the carriage escapement in its operated position, and

Fig. 9 is a similar view of the skip mechanism 25 which controls the limited movement of the card carriage over a predetermined field of a card, said release and skip mechanisms having certain elements in common which are shown in both of said figures and other elements which are omitted from one or the other figures for purposes of clarity in illustration.

In the preferred form illustrated, the invention is shown as comprising a base 10 supporting, on its rear portion, the vertically disposed and forwardly inclined end members 11 which are joined by the horizontally extending front and rear supports 12 and 13. These supports carry the spaced, stationary bed plates 14 each of which is formed in two sections (Fig. 4) and adapted to receive thereon a record card 15 which is moved along said bed plates by a carriage immediately after each punching operation. Said carriage, generally indicated by the numeral 16, is movable along the front and rear guide rails 17 and 18, the former being secured to the end members 11 while the rail 18 is carried by the rear support 13. The main or body portion of the carriage comprises a front plate 19 and a rearwardly spaced rack plate 20 between which is interposed the skip bar 21 having slots or openings 22 therein to be utilized in the skipping operation, later to be described. Adjacent each end of the carriage and mounted between the plates 19 and 20 thereof are the two upper guide rollers 23 engaging the upper edge of the rail 17, while

an intermediate depending portion 24 of said front plate 19 has journaled thereon the lower guide roller 25 which travels along the lower edge of said rail 17 as the carriage is moved back and forth. At opposite ends of the carriage 16, the same mounts rearwardly extending studs 26 which support a bar 27, and extending rearwardly from an intermediate point on said bar is another stud 28 which carries the rear guide roller 29 interposed between the lower edge of the support 13 and the rail 18, thus completing the guiding means for said carriage. As best shown in Fig. 4, the bar 27, adjacent one end thereof, carries a rigid finger 30 which extends upwardly through the space between the bed plates 14 and provides a stop for one end of the card 15 when the latter is placed upon said plates preparatory to a punching operation, and at the opposite end of said bar 27 the same supports a similar finger 31 on which is resiliently mounted a catch 32 for engaging the adjacent end of said card to thus retain the same in proper position for punching.

The drive for the carriage 16 by which the same is advanced upon each operation of one of the keys of the machine, comprises a spring motor 33 of any conventional type supported upon a plate 34 secured to the rear surface of the front support 12 at 35, and joined to the front rail 17 by studs 36. The shaft of said motor carries a pinion 37 which meshes with a rack 38 secured to the carriage 16 by bolts 39 that extend through the front and rack plates 19 and 20, as shown in Fig. 3. Through this arrangement, as the carriage is moved to the right, as viewed in Fig. 1, preliminary to a punching operation, the pinion 37 will be driven by the rack 38 to energize the spring of the motor 33 so that it will advance the carriage to the left under the control of an escapement mechanism, after each punching operation has terminated.

The escapement mechanism, the various controls of which will be hereinafter described, comprises a ratchet 40 journaled for rotation on the front support 12 and driven by pinion 41 meshing with the carriage rack 20. A pawl plate 42 is carried on the front end of a rocker shaft 43 journaled in the bearing plates 44 extending upwardly from the supports 12 and 13. A block 45 doweled to said shaft 43 is provided with an upward extension 46 which engages a stud 47 on said plate 42 so that when the shaft 43 is rocked this motion will be transmitted to the plate 42 against the tension of its retractile spring 48 and thus engage the pawl 49 fixed on said plate with the ratchet 40, this being the first movement of the escapement. To so rock the shaft 43, the same has secured thereto at 50 a bail 51 which is key-controlled in a manner to later appear so as to be depressed at each punching or column-spacing operation. The escapement further includes a second pawl 52 mounted intermediate its ends on the shaft 43 in juxtaposition to the plate 42 for a movement relative to said shaft and to the plate 42 when accomplishing the carriage-release or field-skipping operations to be described. However, when the escapement is controlled by the bail 51, as in punching and spacing operations, the pawl 52 is moved with the plate 42 by engagement of a stud 53 on said plate with the upper portion of the pawl, and thus the lower extremity of the latter is disengaged from the ratchet 40 following the engagement of the pawl 49 therewith. The pawl 52 is thereafter restored to normal, to-

gether with the plate 42, by its retractile spring 54. During this operation of the escapement, the spring motor is allowed to advance the carriage a distance equal to the space between two adjacent columns of the card 15, as is well understood in the art.

A punch die 55 is mounted on the supports 12, 13 intermediate the ends thereof and forms a card chamber 56 through which the card 15 moves in one direction when the carriage 16 is initially adjusted for a punching operation, and in the opposite direction as the carriage is advanced during said operation. A plurality of punches 57 are supported in said die 55 and each is provided with a compression spring 58 which normally urges its punch upwardly and restores it to the normal position thereof after the punch has been depressed to perforate an index point in a column of the card 15, the number of such punches being equal to the number of index points in said column.

The operating mechanism for said punches comprises a key board, generally indicated by the numeral 59, which, for convenience of the operator, is mounted upon the base 10 to one side thereof and in forwardly offset relation to the carriage 16. Said key board comprises the vertical side plates 60 that support the upper and lower spaced plates 61 in which are slidably mounted the shanks 62 of the depressible keys 63 of which there are fourteen, eleven being assigned as numerical keys while the remaining three are utilized to control the column-spacing, carriage-release and field-skipping operations, as designated in Fig. 1. Joining the side plates between the plates 61 are two tie rods 64 which provide pivotal supports for a plurality of bell cranks 65, one for each of the keys 63. Each crank 65 is provided at one end with a roller or stud 66 engaging in a yoke 67 formed on the shank 62 of its associated key so that upon depression of the latter the bell crank will be rocked about its pivot 64. The opposite end of each of the bell cranks 65, with the exception of the two 45 associated with the Release and Skip keys, has a slotted connection with the front end of an actuator element 68. These twelve actuators extend rearwardly in transverse relation to the path of travel of the carriage 16 and through a framework consisting of upper and lower plates 69 mounted upon the supports 12, 13. Each actuator is normally urged rearwardly by a spring 70 connected thereto and to the upper plate 69, and the rear ends of all of the actuators are provided 50 with a common support 71 upon which they rest in the normal position thereof, shown in Figs. 2 and 3. Said support 71 is carried by a rock shaft 72 mounted in bearings 73 attached to the rear support 13, and is yieldably held in its normal supporting position by a coil spring 74 connected to the lower plate 69 and to the upper end of an arm 75 secured on said shaft. The rocking movements of the shaft 72, and consequently of the support 71, are limited by contact of the upper and lower portions of the arm 75 with the support 13.

Each actuator 68 has associated therewith a trip member 76 slidably mounted for vertical movement in the frame plates 69 and provided thereon with a roller 77 normally engaging in a recess 78 formed in the upper edge of its actuator and constituting a cam surface by means of which the trip 76 is forced upwardly when the actuator is pulled forwardly by depression of its key 63. The upper end of each trip 76 contacts one end

of a rocker arm 79 individual thereto and pivoted intermediate its ends to one of the brackets 80 mounted on the top plate 88. The other end of said arm 79 has pivotally depending therefrom a plunger 81 slotted to receive a guide rod 82 carried by the bearing plates 44. The lower free end of each plunger 81 rests upon the upper end of its associated punch 57 and also upon the escapement bail 51 so that as the plunger is depressed by the rocking of the arm 79 it will force its punch downwardly to perforate the card 15 and, at the same time will swing the ball 51 downwardly to rock the shaft 43 and thus accomplish the initial operation of the escapement mechanism which involves the rocking of the 15 plate 42 to engage the pawl 49 with a tooth of the ratchet 40. Restoration of the punch is accomplished by its spring 58 which also restores the operating elements for the punch in a manner which will appear in the course of the description. The same action above described in connection with a numerical key also takes place when the Space key is depressed to advance the carriage 16 one step, but without effecting a 20 punching operation. The actuator 68 shown in Fig. 2 is the one associated with the space key and is operatively connected to the bell crank 65 at the left of said figure and to the trip member 25 76 fully shown at the extreme left position. Through said trip member, the associated rocker arm 79 will be operated and its plunger 81, which does not engage a punch, will then depress the bail 51 to initially operate the escapement mechanism. Restoration of the space key plunger and its associated elements is effected by the coil 30 spring 83 (Fig. 3) connected at one end to a pin 84 extending laterally from the rocker arm 79 and at its other end to a pin 85 screwed into the side of the support 13.

When either the space key or any one of the 40 numerical keys has been fully depressed and the punch of the numerical key has reached the extremity of its down stroke, the operated actuator 68 will have been moved forwardly to the dotted line position shown in Fig. 6 in which the lower extremity of the cam surface 86 at the end of the actuator has passed beyond the support 71 in the dotted line or normal position thereof and, consequently, the lower edge of the actuator will no longer be engaged by said support and held in its normal plane thereby. This condition is utilized to accomplish the dual function of first, disabling or rendering inoperative all actuators, including the operated one, until the latter has been restored to its normal rearward position by the full release of the operated key and, secondly, of transferring control of the escapement mechanism from said key to the punch spring 58 or the spring 83, as the case may be, whereby the secondary or final escapement operation will, after completion of punching, take place to advance the carriage 16 to its next position irrespective of the position of the operated key. By thus disabling all the actuators and removing control of the escapement mechanism from the operated key, complete advancement of the carriage is obtainable before another key can be depressed to effect a second punching operation because, as will presently appear, depression of said other key before complete restoration of the first key will result only in a forward movement of the actuator of said other key without operation of the trip member 76 associated with said actuator. However, it will be understood that the present construction permits of two or more keys being depressed 45

simultaneously to punch a like number of perforations in the same column of the card, as is sometimes desired.

Referring again to the condition mentioned above with regard to Fig. 6, it will be apparent that when the operated actuator has reached the dotted line position, which condition exists when the punch 57 is fully depressed and its spring 58 is under compression, said spring will immediately force the punch upwardly because the lower edge of the actuator is no longer engaged with the support 71 and the latter is therefore ineffective to hold the actuator in its normal plane in which it would otherwise counteract the tendency of the spring 58 to expand. Consequently, under the influence of the spring expansion, the punch will start its restoring or return stroke and thus reverse the initial movements of the plunger 81, the rocker arm 79 and the trip member 76. The downward movement of the latter member whose roller 77 is at this point engaged with the upper edge of the actuator rearwardly of the recess 78, having moved out of said recess upon the forward or primary movement of said actuator, exerts downward pressure upon the actuator to move it about its pivotal connection with the bell crank 65 to the full line position of Fig. 6. This movement takes place even though the operated key is held in its fully depressed position, and results in the cam surface 86 of the actuator forcing the support 71 from the dotted to the full line position of Fig. 6. The slight lowering of the upper edge of said support occasioned by this movement and the consequent dropping of the other actuators 68 and their trips 76 by their own weight, is sufficient to prevent a full operation of any one of the rocker arms 79 and its punch should another key 63 be depressed at this time because the cam surface 78 will be ineffective to fully raise the associated trip 76 and the punch 57 will therefore not be lowered sufficiently to engage the card 15. Therefore, it will be apparent that all the actuators are now disabled for purposes of operating their respective punches and this condition holds until the operated actuator completes its secondary or rearward movement, which occurs when the key therefor is fully restored.

Before proceeding with the description of the secondary movement of the actuator, it will be noted that as soon as the operated punch starts its restoring movement under the influence of its spring, the plunger 81 is raised and thereby removes pressure from the bail 51. During the initial escapement movement which engaged the pawl 49 with the ratchet 40 and disengaged the pawl 52 therefrom, the springs 48 and 54 for the plate 42 and pawl 52, respectively, were tensioned and now, as soon as pressure is relieved from the bail 51 said springs 48 and 54 act to reverse the movements of said plate and pawls to permit the ratchet 40 to turn and, through its pinion 41 and rack 20, to advance the carriage one step. The bail 51 is thereby restored to normal because of the fact that the stud 47 (Fig. 5) on the plate 42 turns the block 45 through its extension 46, said block being fixed to the rock shaft 43 of said bail, as previously described. Thus, it is seen that immediately upon full depression of a key 63 and even before pressure is removed therefrom to permit it to restore, the control of the escapement mechanism is shifted from said key to the punch spring. During the initial stage of the secondary action of the escapement mechanism while the pawl 49 is disengaging from its tooth, sufficient time elapses for the punch to disengage itself

from the perforated card before the ratchet 40 is released to step the carriage. This same operation of the escapement occurs when the Space key is depressed except that, in this instance, the raising of the plunger 81 associated with said key is controlled by the recoil of the spring 83 connected to the rocker arm 79 that carries said plunger.

Returning now to the action of the actuator described in connection with Fig. 6, and by reference to Fig. 7, it will be seen that as soon as pressure on the operated key is relieved the spring 70 of the actuator will continue the secondary movement of the latter by pulling it rearwardly, this phase of said secondary movement being a combined linear and pivotal one. During the same, the rear extremity of the actuator will force the support 71 further to the left, as shown by the position in Fig. 7, until the lower end of the arm 75 contacts the support 13, whereupon the cam surface 86 will ride upwardly on the support 71 until the lower edge of said surface clears the upper edge of said support. The spring 74 connected to the arm 75 then restores said support to its normal position so as to raise all actuators to their normal planes, and the rearward movement of the operated actuator continues under the influence of its spring 70 until the roller 77 of the associated trip member 76 again engages in the actuator recess 78, as shown in Fig. 2. The completion of the secondary movement of the actuator following disengagement of the cam surface 86 with the support 71 and the restoration of said support to its normal position occur at the same instant and upon complete restoration of the operated key. Until then, depression of another key will be premature and will merely result in a forward and downward movement of its actuator without fully operating any of the punches or the escapement mechanism.

The mechanism, shown in Fig. 8, by means of which the carriage 16 is fully released to its normal position, will now be described. This operation is effected by depression of the release key and involves a control of the escapement mechanism such that the pawl 52 thereof will be disengaged from the ratchet 40 and held thus until the carriage has been moved by the motor 33 to its extreme left hand position shown in Figs. 1 and 5. This release mechanism and the skip mechanism shown in Fig. 9 and later to be described, have a common shaft 87 mounted in suitable bearings 88 carried by the front support 12 and with which is associated a bail 89 also common to both mechanisms. The shaft 87 supports elements of both mechanisms but, for the sake of clarity in illustration, such elements as are involved in the operation of the skip mechanism only are omitted from Fig. 8 and the same is true with respect to Fig. 9 as to those elements which concern only the release mechanism. The latter is shown in its operated position with the release key 63 depressed, such movement being limited by engagement of a pin 90 on the key shank 62 with the top plate 61 of the key board framework. Upon depression of said key, its bell crank 65 is rocked about the supporting rod 64 and, through the link 91, rocks the arm 92 to the position shown, against the action of the return spring 93 and about the shaft 87 on which said arm is freely mounted. The said arm is provided with a flat surface 94 that constantly engages the bail 89 so as to swing the same downwardly relative to said shaft 87 which supports said bail by means of a block 95 loose on the shaft and by projecting said

shaft through the angular extension 96 of said bail. A cam member 97 is secured to the bail 89 and as the latter is swung downwardly said cam engages a pin 98 projecting from the escapement pawl 52 to swing the same to its release position and relative to the rock plate 42 and against the tension of its return spring 54. Two normally opposed but disengaged latches 99 and 100 are provided for the purpose of retaining the cam 97 and, consequently, the pawl 52 in their operated positions during the movement of the carriage to its full release position. The latch 99 is pivotally mounted on the rod 64 and urged against a stop 101 (Figs. 1 and 3) on the side plate 61 by a coil spring 102, while the latch 100 is loose on the shaft 87 and contacted by the bail 89 so that as the latter is operated the latch 100 is swung forwardly to interengage with the latch 99 and thus hold the bail 89 and cam 97 in their operated positions during the release movement of the carriage. As the full release position is approached, an abutment 103 mounted on top of the skip bar 21 will contact the interposer stop 104 secured to the adjacent end of the shaft 87 and now in the path of said abutment. This contact shifts the shaft 87 linearly to the left and, in so doing, a collar 105 secure on said shaft will similarly move the block 95 and, consequently, the bail 89 to which the block is secured. The movement of the bail shifts the attached cam 97 to permit restoration of the pawl 52 by its spring 54 and said cam, in turn, moves the latch 100 to the left to offset and disengage it from the latch 99, thereby releasing said cam and bail for their return or upward swinging movement under the influence of the spring 93 which now rocks the arm 92 about the shaft 87 in a rearward direction so that its surface 94 will produce said swinging movement. The release key is also restored by said spring 93 and the movement of said bail turns the latch 100 with it by reason of the contact between the two elements. When the shaft 87 was shifted as described, it compressed a spring 106 (Figs. 1 and 9) coiled thereabout, and upon the next movement of the carriage to the right after its release, which movement frees the abutment 103 from the stop 104, said spring becomes effective to return the shaft linearly to its normal position. In so doing, a collar 107 (Fig. 9) fixed to the shaft 87 and abutting the latch 100 (Fig. 1) moves said latch and the cam 97 along said shaft to their normal positions in which said latch is again opposed to but free from the latch 99. Since the cam 97 is secured to the bail 89, the latter will also be restored to normal by the return of the cam, and the parts are again ready for another release operation.

The skip mechanism which enables the carriage 16 to be advanced predetermined distances upon operation of the skip key 63, will now be described. In Fig. 9, this skip mechanism is shown in its operated position wherein the downward movement of the key 63 is limited by engagement of a pin 108 on the key with the top plate 61. The depression of the key rocks its bell crank 65 to the position shown and, through the link 91, swings the arm 110 forwardly against the tension of the return spring 111. Said arm 110 carries a laterally projecting pin 112 which engages an arm 113 secured on the adjacent end of the shaft 87 and thus the forward movement of the arm 110 and its pin 112 will turn the shaft 87. Also, by virtue of a flat surface 114 formed on the arm 110 and engaged with the bail 89, the latter will be swung downwardly to its operated

position to actuate the cam 97 in the same manner and with the same result as described in connection with the release operation. Again, as in the latter operation, the latches 99 and 100 are interengaged and, in addition, a latch 115 carried by the collar 107 fixed on the shaft 87 is turned with the latter to interengage with a latch 116 supported on the rod 64 and urged against the stop pin 101 by the spring 117. The cam 97 is thus latched in its operated position by both sets of latches so as to retain the pawl 52 out of engagement with the ratchet 40 while the carriage 16 advances. When the shaft 87 is turned, the interposer stop 104 secured thereon is swung to a position in the path of the skip stop 118 mounted in a preselected one of the openings 22 formed in the skip bar 21. Therefore, said stop 118 will contact the interposer 104 to stop the carriage at the desired position and will shift the shaft 87 and bail 89 linearly in the same manner as above described in connection with the release operation. The shifting of the shaft and bail in this instance again results in movement of the cam 97 to the left and the consequent disengagement of the latch 100 from the latch 99. Also, the shifting of the shaft with the collar 107 thereon releases the latch 115 from the latch 116. Release of pressure upon the skip key permits the spring 111 to pull the link 109 and arm 110 rearwardly to complete the restoration of said key and, as said arm 110 is thus moved, it retracts the pin 112 so that the spring 119 connected to the arm 113 will act to assist the spring 111 and also swing said arm rearwardly to thus reverse the turning movement of the shaft 87, thereby shifting the interposer stop 104 out of the path of the skip stop 118. When this is accomplished, the spring 108 on the shaft 87 returns the latter linearly to its normal position to again shift the latches 100 and 115 to their opposed positions relative to the latches 99 and 116, respectively. As the shaft 87 is rotatively restored, the latch 115 is carried therewith and by reason of the engagement of its flat surface with the bail 89 the latter is also swung upwardly to its normal position. Restoration of the bail also returns the latch 100 to normal and the parts are then ready for another skip operation.

The carriage 16 is provided with a finger piece 120 for moving the same to a punching position and, on the base 10 alongside the key board 59 and in front of the carriage, there is provided a card rack 121 for the convenience of the operator in feeding cards to said carriage.

What is claimed is:

1. In a card punching machine, a plurality of punches having operative and return strokes, operating means for said punches, key-controlled elements positioned below and operatively associated with said operating means for actuating the same to effect the operative strokes of said punches, an operating key for each of said controlled elements, a card carriage movable in operative relation to said punches, an escapement mechanism for said carriage having primary and secondary movements to advance the same, means actuated by each of said keys to effect the primary movement of said escapement, and means to maintain said controlled elements in operative association with said punch operating means during said primary movement and operated by one of said controlled elements at the conclusion of said primary movement to disassociate said element and its key from the operated punch so that the secondary movement of said escapement

will be shifted to the return stroke of said punch for accomplishment thereby independently of said controlled element.

2. In a card punching machine, a plurality of punches having operative and return strokes, a plurality of keys for operating said punches and also having operative and return strokes, a card-supporting carriage movable in cooperative relation to said punches, means including an escapement mechanism for advancing said carriage to a succeeding punching position following each punching operation, mechanical means controlled by the return stroke of an operated punch and independently of the return stroke of the key for said punch for actuating said escapement mechanism to advance said carriage, and means to disable all said keys at the conclusion of the operative stroke of one of them and until its return stroke is completed.
3. In a card punching machine, a plurality of punches, a selectively controlled actuator for each punch normally having operative connection therewith and having a primary rectilinear movement, means comprising said operative connection and activated by its actuator during said movement thereof for operating the associated punch, a card carriage movable in cooperative relation to said punches, means to advance said carriage to a succeeding punching position each time a card is punched, and means similarly to disable the operative connections of all the actuators with their respective punches after a card has been punched and for a period subsequent to the full advancement of said carriage to said succeeding punching position.
4. In a card punching machine, a plurality of punches having operating and restoring movements, a selectively controlled actuator for each punch, a card-supporting carriage movable in cooperative relation to said punches, means to progressively advance said carriage to a succeeding punching position upon each operation of one of said actuators, means to support said actuators in cooperative relation to their respective punches during the operating movement of one of said punches, and means to disassociate said supporting means from the actuators of the remaining punches during the restoring movement of said punch.
5. In a card punching machine, a plurality of punches having operating and restoring movements, a selectively controlled actuator for each punch, a card-supporting carriage movable in cooperative relation to said punches, means to progressively advance said carriage to a succeeding punching position upon each operation of one of said actuators, and a movable support for said actuators maintaining the same in cooperative relation with said punches during the operating movement of one of them and operated by the actuator of the latter punch during the restoring movement of said punch to operatively disconnect the remaining actuators from their respective punches.
6. In a card punching machine, a plurality of punches, a selectively controlled actuator for each punch having primary and secondary movements, a card-supporting carriage progressively advanced to place the card thereon in punching position relative to said punches, means to so operate said carriage, and a support for said actuators maintaining the same in operative relation to their respective punches during the primary movement of one of said actuators, said support being thereafter controlled by the sec-

ondary movement of said actuator to operatively disconnect all actuators from their respective punches until said secondary movement of an actuator is completed.

7. In a card punching machine, a plurality of punches having operating and restoring strokes, a selectively controlled actuator for each punch having a linear movement in one direction during the operating stroke of its punch and a pivotal movement at the termination of said stroke, and further having a combined pivotal and linear movement in the opposite direction during the restoring stroke of said punch, a card-supporting carriage progressively advanced to place the card thereon in punching position relative to said punches, means to so operate said carriage, a support for said actuators maintaining the same in operative relation to their respective punches until the first named linear movement of one of said actuators has been completed, said support being operated by said actuator during said combined movement thereof to disassociate all actuators from their punches until said combined movement is completed, and means thereupon operable to restore said support to its supporting position.

8. In a card punching machine, a plurality of punches having operating and restoring strokes, a selectively controlled actuator normally operatively connected to each punch and having operating and return movements, a card-supporting carriage movable in cooperative relation to said punches, means to progressively advance said carriage to a succeeding punching position upon completion of each operating movement of one of said actuators, and releasable means to maintain said actuators operatively connected to their respective punches during the operating stroke of one of them, the release of said means being controlled by the actuator of an operated punch during the restoring stroke of the latter to render all actuators ineffective until the return movement of said actuator is completed.

9. In a card punching machine, a punch, an actuator therefor having operating and return strokes, and a movable supporting means to releasably maintain the actuator operatively connected to said punch during the operating stroke of said actuator, the latter having means operable during the return stroke of said actuator to move said supporting means to an inoperative position.

10. In a card punching machine, a plurality of punches, an actuator for each of them having operating and return strokes, a carriage movable to an advanced position relative to said punches each time one of said actuators is operated, and a common support for said actuators relative to which the latter move during the operating strokes thereof, each actuator contacting said support during said return stroke to shift said support to an inoperative position until said actuator completes its return stroke.

11. In a card punching machine, a plurality of punches, a selectively controlled actuator for each punch having a sliding movement during a punching operation and a pivotal movement at the termination thereof, means to restore each punch after a punching operation, means operable in response to said restoring means to effect said pivotal movement of the associated actuator, a common support for said actuators effective during said punching operation to maintain said actuators in operative association with their respective punches, and means to operate said associated actuator after its pivotal movement so

as to render said support inoperative until the last named operation of said actuator is completed.

12. In a card punching machine, a punching mechanism having a normal position, key-operated actuators each controlling an element of said punching mechanism, and means directly operated by each of said actuators, following the punching of a card by its associated punching element and before complete restoration of said punching mechanism to normal, to render ineffective all other actuators.

13. In a card punching machine, a punching mechanism having a normal position, key-operated actuators each operable to control an element of said punching mechanism and each having a normal position, and a pivoted support for said actuators moved from a normal supporting position by the operation of one of said actuators, following the punching of a card, to render ineffective all said actuators until said operated actuator and its key have restored to normal, and means to so restore said actuator and key.

14. In a card punching machine, a plurality of punches having operating and restoring strokes, a selectively controlled actuator for each punch having one movement during the operating stroke of its punch and a different movement after the termination of said operating stroke, and a support for said actuators operable during the first named movement to maintain said actuators in operative association with their respective punches while a punch is making its operating stroke, each actuator having means operable during and until the termination of said different movement to remove said support from its operative position.

15. In a card punching machine, a plurality of punches having operating strokes, an actuator associated with each punch, a movable support maintaining all said actuators operatively connected to their respective punches, means controlled by each actuator for producing an operating stroke of its associated punch, and means forming a part of each actuator for engaging said support at the termination of said operating stroke to move said support to an inoperative position.

16. In a card punching machine, a plurality of punches, key controlled actuators therefor each having a normal position and an operating movement, means directly responsive to said movement of an actuator for operating one of said punches, and means also responsive to said movement to thereafter similarly disable all actuators and maintain them in disabled condition until the operated actuator has returned to normal.

17. In a card punching machine, a plurality of punches, operating mechanism therefor comprising a plunger for each punch, a rocker arm supporting said plunger in operative relation to its punch, a sliding trip element for said arm, and an actuator having a cam surface engageable with a portion of said trip element to slide the same for rocking said arm when said actuator is operated.

18. In a card punching machine, a plurality of punches, a movable card-supporting carriage cooperating with said punches and operable to progressively advance a card preliminary to a punching operation, operating mechanism for said punches comprising a plunger for each punch, a rocker arm supporting said plunger in operative relation to its punch, actuators for said punches extending transversely to the direction of move-

ment of said carriage and each operable to rock one of said arms to depress its plunger, and an escapement controlled by the depression of said plunger to advance said carriage.

19. In a card punching machine, a plurality of punches, a card-supporting carriage cooperating with said punches and operable to progressively advance a card preliminary to a punching operation, operating mechanism for said punches comprising a plunger for each punch, a rocker arm supporting said plunger in operative relation to its punch, actuators for said punches each operable to rock one of said arms to depress its plunger, a movable support for said actuators maintaining the same in operative relation to said rocker arms during the operating stroke of a punch, and means forming a part of each actuator operable at the termination of said operating stroke to move said support to an inoperative position.

20. In a card punching machine, a plurality of punches, an actuator for each punch having a primary rectilinear operating movement and a secondary gravitational movement to an inoperative position, means operatively connecting each actuator to its punch during said primary movement, and means controlled by each actuator during its secondary movement to similarly render inoperative the connecting means of all said actuators.

21. In a card punching machine, a plurality of punches, an actuator for each punch having primary and secondary movements and provided thereon with a cam surface, means to effect the primary movement of an actuator, means responsive to said actuator during its primary movement for operating its punch to perforate a card, and means controlled by said cam surface during the secondary movement of said actuator to render ineffective all said actuators.

22. In a card punching machine, a plurality of punches, an actuator for each punch having primary and secondary movements and provided thereon with a cam surface, means to effect the primary movement of an actuator, means responsive to said actuator during its primary movement for operating its punch to perforate a card, a movable support for said actuators maintaining the same in operative association with said responsive means during the primary movement of one of said actuators, and means to produce the secondary movement of said actuator, the cam surface of the latter moving said support, in the initial stage of said secondary movement, to a position wherein said responsive means is operatively disconnected from all said actuators.

23. In a card punching machine, a plurality of punches, an actuator for each punch having primary and secondary movements, means to effect the primary movement of an actuator, means responsive to said actuator during its primary movement for operating its punch to perforate a card, a carriage for said card movable to a succeeding punching position upon each operation of an actuator, an escapement for said carriage controlled by said responsive means, and means directly operated by said secondary movement of said actuator to prevent operation of another punch until said secondary movement is completed.

24. In a card punching machine, a plurality of punches, an actuator for each punch having primary and secondary movements and provided thereon with a cam surface, means to effect the primary movement of an actuator, means re-

sponsive to said actuator during its primary movement for operating its punch to perforate a card, a carriage for said card movable to a succeeding punching position upon each operation of an actuator, an escapement for said carriage controlled by said responsive means, and means controlled by said cam surface in the initial stage of the secondary movement of said actuator to prevent operation of another punch until said secondary movement is completed.

25. In a card punching machine, a plurality of punches, actuators therefor having primary and secondary movements, means responsive to the primary movement of an actuator for operating one of said punches to perforate a card, restoring means for said punch initiating the secondary movement of said actuator, and means directly operated by said secondary movement for preventing operation of another punch until completion of the latter movement.

26. In a card punching machine, a plurality of punches, an actuator for each punch having a normal position and primary and secondary movements and provided thereon with a cam surface, means to effect the primary movement of an actuator, means responsive to said actuator during its primary movement for operating its punch to perforate a card, a carriage for said card movable to a succeeding punching position upon each operation of an actuator, an escapement for said carriage controlled by said responsive means, a movable support for said actuators maintaining the same in operative association with said responsive means during said primary movement, said support being moved by the cam surface of said actuator during the initial stage of the secondary movement thereof to operatively disconnect all other actuators from their respective punches until said carriage has reached a succeeding punching position and said actuator has restored to normal, and means to complete the secondary movement of said actuator and restore it to normal.

27. In a card punching machine, a plurality of punches, a carriage movable relative to said punches to progressively advance a card to various punching positions, a key board offset laterally to one side of said carriage and comprising a plurality of keys, an actuator operated by each key for movements transverse to that of said carriage, a plunger for operating each punch, and a rocker arm for each plunger operated by one of said actuators.

28. In a card punching machine, a plurality of punches, a carriage movable relative to said punches to progressively advance a card to various punching positions, an escapement for advancing said carriage each time a card is punched, a key board offset laterally to one side of said carriage and comprising a plurality of keys, an actuator operated by each key for movements transverse to that of said carriage, and means controlled by the operation of each actuator after a card has been punched to render ineffective all other actuators until an operated key is restored to normal.

29. In a card punching machine, a plurality of punches, a carriage movable relative to said punches to progressively advance a card to various punching positions, an escapement for advancing said carriage, a key board offset laterally to one side of said carriage and comprising a plurality of keys, an actuator operated by each key for movements transverse to that of said carriage, a plunger for operating each punch and

for controlling said escapement, a rocker arm for each plunger operated by one of said actuators, and means controlled by the operation of each actuator to render ineffective all other actuators until an operated key is restored to normal.

30. In a card punching machine, a plurality of punches, a carriage movable relative to said punches to progressively advance a card to various punching positions, an escapement for advancing said carriage, a key board offset laterally to one side of said carriage and comprising a plurality of keys, an actuator operated by each key for movements transverse to that of said carriage, a plunger for operating each punch and for controlling said escapement, a rocker arm for each plunger operated by one of said actuators, and a movable support for said actuators under the control of each of them to render all other actuators ineffective until an operated key is restored to normal.

31. In a card punching machine, a punch, an actuator for said punch operable from a normal position through primary and secondary movements, means to effect primary movement of said actuator to operate said punch, a support maintaining operative connection between said punch and said actuator during the primary movement of the latter and operated by said actuator during its secondary movement to prevent another operation of said punch until said actuator returns to normal position, and punch restoring means controlling a part of said secondary movement of said actuator.

32. In a card punching machine, a plurality of punches, actuators for said punches, keys for operating said actuators, means operatively connecting said actuators to said punches, and means to releasably retain said actuators in cooperative relation to said connecting means until a card has been punched by the operation of one actuator, said retaining means being thereupon released by said actuator to prevent operation of a punch by another actuator until the key of the first named actuator is restored.

33. In a card punching machine, a plurality of punches having operating and restoring strokes, an actuator for each punch having primary and secondary movements, a key for operating each actuator through its primary movement to effect the operating stroke of its associated punch, restoring means for said punch operable to control a portion of the secondary movement of said actuator, means to complete said secondary movement, and means influenced by said secondary movement to render ineffective all said actuators until the restoring stroke of said punch has completely withdrawn it from a card and an operated key has been restored.

34. In combination, a plurality of actuators having primary and secondary movements, means to effect said primary movements, a record supporting carriage, means responsive to said primary movements for creating identifying indicia on the record supported by said carriage, means to advance said carriage upon each operation of one of said actuators, and a movable support for said actuators effective during the primary movement of any one of them to maintain the same in cooperative relation to said responsive means and moved to a non-supporting position by the secondary movement of an actuator so as to render all actuators ineffective until said secondary movement is completed.

35. In combination, a plurality of actuators having primary and secondary movements, 75

means to effect said primary movements, other means to effect said secondary movements, actuator-responsive means operated by the primary movement of one of said actuators, and means to maintain said actuators effective during the primary movement of said actuator and to disable all said actuators until the secondary movement of said actuator is completed.

36. In combination, a plurality of actuators having primary and secondary movements, means to effect said primary movements, other means to effect said secondary movements, actuator-responsive means operated by the primary movement of one of said actuators, and a movable support for said actuators effective during said primary movement to maintain all actuators in cooperative relation to said responsive means and moved to a non-supporting position by the secondary movement of said actuator so as to render all said actuators ineffective until said secondary movement is completed.

37. In combination, a plurality of actuators each having a primary and a secondary movement, means to effect said primary movement, other means to effect said secondary movement, actuator-responsive means operated by the primary movement of one of said actuators, and means controlled by the secondary movement of said actuator to disable all said actuators until said secondary movement is completed.

38. In a card punching machine, a plurality of punches, a carriage movable to position a card relative to said punches, an escapement mechanism for controlling the movement of said carriage, releasing means for said mechanism operable to effect the complete release of said carriage, said releasing means including a shaft, a bail supported by and movable relative to said shaft during a release operation, means carried by said bail to release said escapement mechanism when the bail is moved, means to retain the bail in its operated position until the carriage is fully released, means thereupon operable to disable said retaining means, and means to then restore said bail and said escapement mechanism.

39. In a card punching machine, a plurality of punches, a carriage movable to position a card relative to said punches, an escapement mechanism for controlling the movement of said carriage, releasing means for said mechanism operable to effect the complete release of said carriage, said releasing means including a shaft having linear movements, a bail supported by said shaft and having rotative movements relative thereto during a release operation, means carried by said bail to release said escapement mechanism when the bail is moved, means to retain the bail in its operated position until said carriage is fully released, means thereupon operable to move said shaft linearly to disable said retaining means, and means to then restore said bail, shaft and escapement mechanism to their original positions.

40. In a card punching mechanism, a plurality of punches, a carriage movable to position a card relative to said punches, an escapement mechanism for controlling the movement of said carriage, releasing means for said mechanism operable to effect the complete release of said carriage, said releasing means including a shaft having linear movements, a bail supported by said shaft and having rotative movements relative thereto during a release operation, means carried by said bail to release said escapement mechanism when the bail is moved, co-

operating latching elements one of which is mounted on said shaft and actuated by the movement of said bail to operatively engage the other latching element so as to retain said bail in its operated position until said carriage is fully released, means thereupon operable to move said shaft linearly to disable said latching elements, and means to then restore said bail, shaft and escapement mechanism to their original positions.

41. In a card punching machine, a plurality of punches, a carriage movable to position a card relative to said punches, an escapement mechanism for controlling the movement of said carriage, a card-field skipping mechanism for said carriage including a skip stop movable with said carriage, a shaft having rotative and linear movements, means controlled by the rotative movement of said shaft for releasing said escapement mechanism, means responsive to the rotation of said shaft to retain said escapement releasing means in its releasing position until said carriage has moved a predetermined distance, and an interposer stop moved by the rotation of said shaft into the path of said skip stop and operated by engagement of the latter therewith when the carriage has moved said distance to shift said shaft linearly to thereby render said retaining means ineffective.

42. In a card punching machine, a plurality of punches, a carriage movable to position a card relative to said punches, an escapement mechanism for controlling the movement of said carriage, a card-field skipping mechanism for said carriage including a skip stop movable with said carriage, a shaft having rotative and linear movements, a bail supported by and movable with said shaft during a skipping operation, means carried by said bail to release said escapement mechanism when said shaft is rotated, means responsive to the rotation of said shaft to retain said escapement releasing means in its releasing position until said carriage has moved a predetermined distance, and an interposer stop moved by the rotation of said shaft into the path of said skip stop and operated by engagement of the latter therewith when the carriage has moved said distance to shift said shaft linearly to thereby render said retaining means ineffective.

43. In a card punching machine, a plurality of punches, a carriage movable to position a card relative to said punches, an escapement mechanism for controlling the movement of said carriage, a card-field skipping mechanism for said carriage including a skip stop movable with said carriage, a shaft having rotative and linear movements, means controlled by the rotative movement of said shaft for releasing said escapement mechanism, cooperating latch elements controlled by the rotation of said shaft to retain said escapement releasing means in its releasing position until said carriage has moved a predetermined distance, and an interposer stop carried by said shaft and moved thereby into the path of said skip stop and operated by engagement of the latter therewith to move said shaft linearly to thereby render said latch elements ineffective.

44. Means to release the escapement-controlled carriage of a card punching machine comprising, in combination, a member movable from a normal

position, means operated by the movement of said member to release the carriage escapement, cooperating latching elements for said movable member made operative by movement of the latter until release of said carriage is accomplished, means thereupon operable to disable said latching elements, and means to then restore said movable member to its normal position.

45. Means to release the escapement-controlled carriage of a card punching machine comprising, in combination, a shaft having a linear movement, means supported by said shaft and having rotative movement relative thereto to release said escapement, means to retain said releasing means in operated position during a predetermined releasing movement of said carriage, and means operable at the conclusion of said releasing movement to shift said shaft linearly to disable said retaining means.
46. Means to release the escapement-controlled carriage of a card punching machine comprising, in combination, a shaft having a linear movement, means having rotative movement relative to said shaft to release said escapement, cooperating latching elements made operative by the rotative movement of said releasing means to retain the latter in operated position during a predetermined releasing movement of said carriage, and means operable at the conclusion of said movement to shift said shaft linearly to disable said latching means.

47. Means to release the escapement-controlled carriage of a card punching machine comprising, in combination, a shaft having rotative and linear movements, means controlled by the rotative movement of said shaft for releasing said escapement in released position, and means operable at the conclusion of a predetermined releasing movement of said carriage to move said shaft linearly and thereby disable said retaining means.

48. Means to release the escapement-controlled carriage of a card punching machine comprising, in combination, a shaft having rotative and linear movements, means controlled by the rotative movement of said shaft for releasing said escapement, means also controlled by the rotative movement of said shaft to retain said escapement in released position, and means operable at the conclusion of a predetermined releasing movement of said carriage to move said shaft linearly and thereby disable said retaining means.

49. In a card punching machine, a plurality of punches, an actuator for each punch having primary and secondary movements, means operatively connecting each actuator to its punch during said primary movement, and means directly operated by each actuator during its secondary movement to render inoperative the connecting means of all said actuators.

50. In a card punching machine, a plurality of punches, an actuator for each punch having primary and secondary movements, means to effect the primary movement of an actuator, means responsive to said actuator during its primary movement for operating its punch to perforate a card, and means directly operated by the secondary movement of said actuator to render ineffective all said actuators.
